[57] ABSTRACT

A vaporizer for use in a medical respirator for supplying a mixture of patient gas and vapor to a patient during an inspiratory period of the respirator. The vaporizer has a source of patient gas connected thereto and a pair of sealed vessels, each having a connection to the source of gas. When the gas is fed to the vessel containing the liquid, the gas therein becomes saturated. A changeover switch is provided in the connection to the vessels so that alternately the supply of gas is fed to the vessels and to a patient via a patient supply connection. Each vessel is provided with means for adjusting the volume therein so as to control the percentage of saturation of the gas which is passed to the patient from the vessels and so as to control the total volume of gas passed to the patient during each inspiratory period.

VAPORIZERS FOR MEDICAL RESPIRATORS

The invention relates to vaporizing means for medical respirators whereby a variable controlled amount of vapor is included in the respiratory gas flow to a patient.

A known type of vaporizer allows patient gas to pass from a source to the patient along one path provided with a first restrictive means or throttle valve and along another path comprising a second restrictive means or throttle valve and a vaporizing chamber containing liquid. The vaporizing chamber is frequently provided with baffles and wicks partially exposed to the gas to assist in the entrainment of vapor from the liquid. The two restrictive means are operated by a common control knob to determine the relative amounts of gas passing through the two paths and, hence, the percentage saturation of the total amount of gas passing to the patient.

Such vaporizers are normally used in "minute/divider" type respirators, i.e. respirators employing a master flow control supplying a constant flow of gas at substantially atmospheric pressure. Calibration curves from such vaporizers show that the percentage saturation is not constant for all flow rates, and they are therefore not suitable for use with intermittent flow. Additionally, such vaporizers require that adjustment of the combined throttle valves does not affect the total flow from source to patient throughout this range of control of saturation percentage. Where this range is relatively large, difficulties are frequently encountered — at least at one end of the control range — which result in a non-linear scale for the saturation control and/or require the throttle valves and the path to the container to have a special construction (e.g. U.K. Patents 966,797 and 1,001,854).

The present invention provides a vaporizer suitable for intermittent flow which avoids the use of linked throttle valves.

From one aspect, the present invention provides a vaporizer comprising a sealed vessel containing a liquid partially filling the vessel, and a path to and/or from the vessel which is periodically alternately connected by changeover switching means to a source of patient gas at a first pressure higher than atmospheric pressure and to a patient, the gas within the vessel being saturated with vapor from the liquid and the percentage saturation of the gas when passed to the patient at a second pressure which is substantially atmospheric pressure being determined by the difference between the first and second pressures.

Preferably the vessel is of adjustable volume in order that both the quantity of gas stored therein during connection to the source and the percentage saturation of gas delivered to a patient may be controlled.

From a second aspect, the invention provides a vaporizer comprising a first sealed vessel containing a liquid, a second sealed vessel, and changeover switching means alternately connecting both vessels in unison to a source of patient gas at higher than atmospheric pressure and to a patient, the gas within the first vessel being saturated with vapor from the said liquid, the percentage saturation of the gas passed to the patient from both vessels being determined by the relative quantities of the gas-and-vapor and gas contained by the first and second vessels respectively, the said quantities also determining the total volume of gas passed to the patient during each inspiratory period. Preferably, the volume of each of the two vessels is adjustable.

The various features of the present invention will be apparent from the following description of exemplary embodiments thereof taken in conjunction with the accompanying drawings, in which:

FIG. 1 shows a vaporizer for a respirator giving a fixed Tidal Volume.

FIG. 2 shows the vaporizer of FIG. 1 modified to enable Tidal Volume to be varied.

In FIG. 1, a fixed pressure source of patient gas is applied to port N2, gas therefrom passing via a line 1 to a port A1 of a changeover valve CO1 which in a first expiratory position, indicated by a solid line, allows passage of the gas to port C1 of the valve. From port C1 the gas passes via a line 7A to a first

volume, partially filled with liquid to a level as indicated by a broken line 3, the volume available for gas and liquid vapor being determined by the position of a piston 9A in a cylinder 8A and by the liquid level. During the expiratory period with valve CO1 establishing a gas passage as shown by a solid line, gas within the volume is saturated, i.e. will take up no more vapor from the liquid. Increase of the pressure of the source will increase the amount of gas relative to vapor in the volume at a given temperature, i.e. will decrease the percentage saturation on release of the volume of gas to atmospheric pressure. A decrease in the source pressure is accompanied by an increase in percentage saturation of the gas. Variation of source pressure also alters the quantity of gas/vapor stored in the first volume, but at a fixed, greater than atmospheric, pressure, gas and vapor have a fixed ratio irrespective of the size of the volume, variation of which by movement of piston 9A merely altering the quantity of gas/vapor stored.

Gas from port N2 also passes via a line 6A to a port A2 of a second changeover valve CO2 which in its first position permits gas to flow as shown by a solid line to a port C2. From this latter port the gas is then passed via a line 7B to a second volume formed within a cylinder 8B by a piston 9B. The quantity of gas stored in the second volume is similarly a product of the gas pressure and size of volume as determined by the position of piston 9B.

Piston rods 10A and 10B control the position of the respective pistons 9A and 9B and mechanical linkage of the rods, indicated by a broken line, is arranged to move the pistons in opposite directions so that the sum of volumes in cylinder 8A and 8B, and hence of the gas/vapor and gas therein, is constant.

In a second inspiratory position of valves CO1 and CO2 gas passages are established, as indicated by broken lines, 35 between respective ports C1, B1 and C2, B2. Ports B1 and B2 are both connected to a common path line 4 leading to a patient and the gas/vapor and gas will therefore flow from the two volumes to the patient, the total amount of gas relative to vapor being determined by the relative positions of the two pistons. The operating means of the mechanical linkage may thus be calibrated in terms of percentage saturation.

In the vaporizer described above, the source pressure and the sum of the volumes are both constant and the Tidal Volume of gas delivered to a patient will also be constant. 45 Decrease of such Tidal Volume may be achieved by curtailing the time during which discharge from the volume occurs, e.g. by providing at least one restriction and switch between ports B1, B2 and the patient and closing the path to the patient before pressure in the volumes has fallen to the minimum. As variable volumes are involved in determining saturation percentage, compensation for alterations in the discharge time constant (Volume $\times$ Flow Resistance) have then to be provided.

50 Preferably such variation of Tidal Volume is also obtained by variation of the two volumes of FIG. 1 as shown in FIG. 2, which also shows means whereby a plurality of patient gases may be mixed in desired proportions.

In FIG. 2, two different patient gas sources are connected to ports N3 and N4 having regulators PR3 and PR4 and flow controls FC3, FC4 respectively in the paths to a common pipe line 11. Preferably the regulators are coupled together and arranged so that they both have a given pressure output or one or the other alone has the given output which may be, for example 60 PSI. With pressure output from both regulators, each flow control determines the amount of gas passing therethrough in unit time and the setting of these controls therefore determines the mixture of gases in line 11 linking their outputs. Pipe line 11 is connected to lines 1 and 6A feeding ports A1 and A2 of changeover valves CO1 and CO2, whose ports B1 and B2 pass gas saturated to a required degree through lines 4 and 6B towards a patient. Two cylinders 8C and 8D are connected to the ports C1 and C2 of valves CO1 and CO2 by lines 7A and 7B respectively. Cylinder 8C has two opposed pistons 9C and 9CC having piston rods 10C and

10CC respectively. Similarly cylinder 8D has pistons 9D and 9DD and rods 10D and 10DD. Cylinder 8C contains a quantity of liquid, for mixing with the gas, whose level is indicated by a broken line 3. A bar 12 is rigidly attached to piston rods 10C and 10D and carries a nut 13 engaged with a threaded rod 14, carried by bearings, not shown, so that it may be rotated by an attached knob 15 to move pistons 9C and 9D and hence adjust the Tidal Volume. Piston rod 10DD is coupled to a bar 16 by means of a pin 17 in slidable engagement with a slot 18 in bar 16, rod 10CC being similarly coupled by a pin 19 co-operating with another slot 20 in bar 16. Bar 16 is arranged to pivot on a pin 21, slidably engaged in a further slot 22 in bar 16, carried by a member 23 so that as piston 9CC moves in one direction, piston 9DD moves in an opposite direction. An extension of bar 16 carries a pivotally mounted nut 24 which is engaged with a threaded rod 25, rotatable in bearings, not shown, to which is attached a knob 26. Rotation of knob 26 will thus cause variation of percentage saturation and its angular rotation may thus be calibrated in such terms.

Depending on the relative amounts of piston movement, the maximum volume available for gas within the cylinders and the desired accuracy of the above scale, a correcting device may be required to compensate for the change in effective volume ratios at high and low percentage saturation settings as Tidal Volume is altered.

This is accomplished in the embodiment described by movement of the pivot 21. Member 23 is arranged to slide in guides, not shown, and has attached arms 27 carrying roller cam followers 28. These are in engagement with the faces of a cam nut 29, which is engaged with rod 14. Nut 29 is guided and prevented from turning by means not shown and will traverse rod 14 during rotation of knob 15 and rod 14 to alter the relative distances between pins 21 and 17, and pins 21 and 19. Nut 29 and pistons 9D and 9C move together, the cam profile being such that the necessary change in pivot position is made to retain calibration of the percentage saturation control.

Although when pivot 21 is not in its midposition, alteration of the percentage saturation control will affect the calibration of the Tidal Volume control, the effect is not large as movement of piston 9DD is still largely compensated by opposite movement of piston 9CC. The effect may be further reduced by arranging that the range of control of percentage saturation available is greater than normally required so that extreme settings are not normally used.

In both FIGS. 1 and 2 gas in the two volumes is, at the commencement of an inspiratory period, at the same pressure as the source, e.g. 60 PSI, and a very rapid flow to the patient's lungs would occur for a short period of time. A flow control, similar to that preceding the known type of vaporizer, between the patient and line 4 is therefore necessary to avoid too rapid inflation of the lungs.

What is claimed is:

1. A vaporizer apparatus for use in a medical respirator, comprising a first sealed vessel containing a liquid, a second sealed vessel, a source of patient gas, a means of supply of gas to a patient, changeover switching means alternately connecting both vessels in unison to said source of patient gas at higher than atmospheric pressure and to said patient supply means, the gas within the first vessel being saturated with vapor from the said liquid, the percentage saturation of the gas passed to the patient from both vessels being determined by the relative quantities of the gas-and-vapor and gas contained by the first and second vessels respectively, the said quantities also determining the total volume of gas passed to the patient during each inspiratory period, and means for adjusting the volume of each of the said vessels including a first adjusting means for varying the volumes of the two vessels in opposite senses to control the percentage saturation of gas passed to the patient, and further including a second adjusting means for varying the volumes in the same sense to control the total quantity of gas and vapor passed to the patient via said means of supply to the patient in an inspiratory period.

5 2. The vaporizer apparatus according to claim 1 further comprising means mechanically interrelating the first and second adjusting means, whereby the adjustment of either one of said first and second adjusting means effecting the two volumes such that the percentage saturation of gas passed to the patient remains substantially constant when the volume of gas passed to a patient during each inspiratory period is changed.

10 3. The vaporizer apparatus according to claim 1 wherein said adjusting means for varying the volume of the two vessels comprises a first movable wall within each vessel movement of which varies the volume of the vessel concerned, said first movable walls being mechanically coupled by a first mechanical coupling means adjustment of which by the first adjusting means causes the volumes of the two vessels to change in opposite senses to control the percentage saturation of gas passed to the patient.

15 4. The vaporizer apparatus according to claim 3 further comprising a second movable wall within each of said vessels, movement of which varies the volume of the vessel concerned, said second movable walls being mechanically coupled by a second mechanical coupling means adjustment of which by a second adjusting means causes the volumes of the two vessels to change in the same sense to control the quantity of gas and vapor passed to a patient via said patient gas supply means in an inspiratory period.

20 5. The vaporizer apparatus according to claim 4 further comprising a third mechanical coupling means interconnecting said first and second coupling and adjustment means, said third mechanical coupling means being arranged to alter the ratio of opposed incremental volume changes made by the first means on operation of the second means, whereby any change in the percentage saturation of gas passed to a patient would otherwise result from a change in the sum of the volumes by operation of the second adjustable means is automatically compensated by said third mechanical coupling means.

25 6. The vaporizer according to claim 4 wherein each vessel is formed by a cylinder, and wherein said movable walls are formed by movably mounted pistons.

30 7. A vaporizer apparatus for use in a medical respirator comprising a first sealed vessel containing a liquid partially filling the vessel, a second sealed vessel, a movable wall within each of said vessels for controlling the volume therein, a source of patient gas for providing a supply of patient gas at a first pressure which is higher than atmospheric pressure, connection means for communicating said source of patient gas to both of said vessels simultaneously, means for supplying gas from said vessels to a patient, changeover switching means for alternately connecting said vessels to said supply of patient gas and the patient so that when the vessels communicate with the supply of gas the gas within said first vessel will become saturated with vapor from the liquid contained therein, means connected to said movable walls for causing adjustment thereof to vary the volume within the vessels so that the degree of saturation of the gas passed to the patient when said vessels are caused to communicate therewith is thereby controlled by the relative amount of vapor saturated gas contained in said first vessel and gas in said second vessel, said amounts being determined by the total volume of gas passed to the patient during each inspiratory period.

35 8. The vaporizer apparatus according to claim 7 wherein said means connected to said movable walls for causing adjustment thereof is controlled so that an incremental change in the volume of said first vessel in one sense will be accompanied by an incremental change of the same magnitude in the opposite sense in the volume of said second vessel so that the combined volume of both of said vessels will remain constant.

40 9. The vaporizer apparatus according to claim 7 further comprising means connected to both said movable walls of said vessels for causing simultaneous adjustment thereof in equal amounts and in the same sense so as to vary the combined volume of said vessels.
